UNITED STATES PATENT OFFICE

2,534,920

CIRCUIT INTERRUPTER

Leon R. Ludwig, Wilkinsburg, and Benjamin P. Baker, Turtle Creek, Pa., assignors to Westinghouse Electric Corporation, East Pittsburgh, Pa., a corporation of Pennsylvania

Application April 30, 1945, Serial No. 591,047

3 Claims. (Cl. 200—150)

1

This invention relates to circuit interrupters in general, and more particularly to contact and arc extinguishing structures and to the mounting and enclosure thereof.

According to our invention, an oil circuit breaker is provided with only one interrupter for 138 kv. or even 220 kv. service, and the low rate of oil deterioration and gas generation makes it entirely feasible to house it in a porcelain or insulating container rather than a thick wall steel tank.

It is a general object of our invention to provide an improved mounting arrangement for a circuit interrupter of either the gas-blast or liquid type. It is a more particular object of our invention to adapt such an improved mounting arrangement to a circuit interrupter of the liquid break type, preferably using an oil-pool construction.

We propose to permit the entire breaker structure to be redesigned using substantially one-half of the parts used in the conventional dead tank type of breaker, i. e., one interrupter, one isolating gap, one bushing, a lighter mechanism, a small tank of insulating material instead of a large steel tank and only a small percentage of the oil formerly used.

Another object is to provide an improved circuit interrupter of the foregoing type with means for minimizing the overall length of the interrupter and minimizing the width of the interrupter. Preferably, we attain such an improved construction by having the movable contact structure telescope within the bushing in the fully open circuit position of the interrupter.

Another object is to provide a high speed contact mechanism for a circuit interrupter of the foregoing type.

Further objects and advantages will readily become apparent upon a reading of the following specification taken in conjunction with the drawings, in which:

Figure 1 is an elevational view of a circuit interrupter embodying our invention;

Fig. 2 is a fragmentary enlarged vertical sectional view of the contact and arc extinguishing structure of the circuit interrupter shown in Fig. 1, the parts being shown in the closed circuit position;

Fig. 3 is an enlarged elevational view partly in section of the improved operating mechanism of our invention, taken substantially along the line III—III of Fig. 4, the parts being shown in the closed circuit position;

Fig. 4 is a sectional view taken along the line IV—IV of Fig. 3, and

2

Fig. 5 shows a modified type of contact operating arrangement.

Referring to the drawings and more particularly to Fig. 1 thereof, the reference numeral 1 generally designates support means at ground potential. The support means comprises suitable structural steel framework including vertically extending supports 2 braced by diagonally extending angle members 3. A base 4 is provided upon which the supporting framework stands.

The circuit interrupter 5 of our invention is supported by the grounded support means 1, and has an upper stationary line terminal 6 and a lower line terminal means 7. The external circuit is connected through the interrupter by the wires 8, 9.

Referring more particularly to Fig. 2, it will be observed that the circuit interrupter of our improved construction comprises an enclosure 19 formed by a casing 11 of porcelain or a material of weatherproof construction. The porcelain casing 11 seats upon a gasket 12 supported by a ring-shaped member 13, in turn supported by a metallic cylinder 14. The cylinder 14 is supported by the circumferential portion of a plurality of spring washers 15, the inner ends of which are forced by bolts 16 toward a casting member 17.

The casting member 17 is supported by a cylindrical insulating tube 18. The upper end of the tube 18 is supported by a ring-shaped member 19 secured by bolts 20 to a metallic ring 21. The metallic ring 21 is secured to a support member 22 by welding or the like, the upper end of the support member 22 in turn being secured to one or more channel members 23 forming a part of the support means 1. A plate 24 is secured by suitable means, not shown, to the support member 22 and supports a high voltage bushing generally designated by the reference numeral 25, preferably of the condenser type intermediate the ends thereof. More specifically, the plate 24 is attached by bolts 24a to a metallic support member 24b, the latter supporting an insulating cylinder 25a through which extends a conducting tube or elongated conductor 25b. Thus the conducting means 28 for the circuit interrupter including the tube 25b extends through the support means 1 by means of the high voltage condenser bushing 25.

An arc extinguishing unit or an extinguishing means, generally designated by the reference numeral 26, is disposed adjacent one end of the conducting means 28 extending through the bushing 25, and terminal means 27 for the inter-

rupter are positioned adjacent the opposite side of the arc extinguishing unit 26 from the conducting means 28.

The longitudinally extending conducting means 28 comprises contact means including a movable rod-shaped contact 29 having a rack 30 formed on its right side, as viewed in Fig. 2, and biased downwardly toward the closed position by a compression spring 74 disposed in a conducting tube 75. A gear 31 meshes with the rack 30 to cause the actuation of the same. Secured to the gear 31 is a pinion 32, the gear and pinion being supported on a pin 33 which passes through two opposed vertically extending support plates 34, 35 carried on the end of the bushing 25, as more clearly shown in Fig. 4.

Meshing with the pinion 32 is a gear segment 36 secured to an arm 37, the latter being pivoted on a bolt 38 and having an integrally formed sleeve portion 39. The sleeve portion 39 has an operating arm 40 integrally formed therewith which makes pivotal connection at 41 to an operating rod 42 formed of a suitable insulating material. The operating rod 42, it will be noted, extends substantially longitudinally of the conducting means 28 and is actuated by a lever 43 making pivotal connection to the operating rod 42 at 44. A shaft 45 serves to rotate the lever 43 and hence to effect reciprocating, substantially vertical motion, of the operating rod 42. Preferably, a bumper mechanism 46 is provided assuming in this instance the form of a compression spring 47 encircling a rod 48 and seating upon a washer member 49 actuated vertically by a portion 50 of the lever 43.

Surrounding the bushing 25 is a current transformer winding 51 to serve as a measure of the magnitude of the current passing through the interrupter. The winding 51 is connected to suitable measuring equipment which will actuate suitable relays, not shown, in response to overload conditions existing in the circuit connected to the interrupter.

From the foregoing description, it will be apparent that the spring washers 15 place the porcelain casing 11 in compression and also place the insulating cylinder 18 in tension. Preferably liquid 52, such as oil, fills the casing to the level indicated by the line 53.

The specific arc extinguishing unit 26 forms no part of our invention and may be of any suitable type. Preferably, however, we employ an arc extinguishing unit of the type described and claimed in U. S. patent application, filed November 11, 1942, Serial No. 465,244, now U. S. Patent 2,406,469, issued August 27, 1946, by Leon R. Ludwig, Winthrop M. Leeds and Benjamin P. Baker and assigned to the assignee of the instant application.

Briefly, such an arc extinguishing unit comprises a pressure-generating contact 54 cooperative with an intermediate contact 55 to form a pressure-generating arc, not shown, in a pressure-generating chamber 56. Oil under pressure, as a result of formation of the pressure-generating arc, is forced upwardly through a pair of vertically extending flow passages 57 and inwardly through a plurality of inlet passages 58 to strike an interrupting arc, not shown, formed by separation of the movable contact 29 from the intermediate contact 55. After striking the interrupting arc, not shown, the oil passes through orifices 59 formed by suitable plate structure to exhaust out of the unit 26 through a plurality of exhaust passages 60. The aforesaid patent de-

scribes the plate structure and the passage configuration of the arc extinguishing unit 26. A compression spring 61 biases the intermediate contact 55 upwardly. Flexible shunts 62 electrically connect the pressure-generating contact 54 with the lower line terminal 7. A compression spring 63 biases the pressure-generating contact 54 upwardly to a limiting position, as defined by the stop 64.

Thus, upon initial upward movement of the movable contact 29, the entire contact structure moves upwardly under the influence of the compression springs 61, 63 until the stop cap 64 strikes the plate 65. Further upward movement of the intermediate contact 55 and the movable contact 29 creates a pressure-generating arc drawn in the pressure-generating chamber 56. Subsequently, the movable contact 29 separates from the intermediate contact 55 when the flange portion 66 of the latter strikes the plate 67 to effect the drawing of an interrupting arc in the interrupting portion 68 of the arc extinguishing unit 26. The oil flow, as previously described, quickly effects the interruption of the interrupting arc, and the movable contact 29 continues its upward motion to place an isolating gap into the circuit while compressing the biasing means 74.

It will be observed that the gear means 69 which we have provided effects a very rapid upward movement of the movable contact 29 to also rapidly effect the interposition of an isolating gap into the circuit. It will furthermore be observed that the movable contact 29 telescopes 35 into the high voltage bushing 25 to thereby minimize the overall length of the breaker.

The arc extinguishing unit 26 has been found not only to give excellent interrupting performance but also to result in very little contamination of the oil. Thus, the relatively small volume of oil contained by the insulating casing 18 is sufficient for long operational life of the interrupter.

For relatively low voltage service, where such rapid separation of the contact structure is not necessary, the operating rod 42 may be directly connected to the movable contact 29 by a pin connection 70 as more fully shown in Fig. 5. Here again the movable contact 29 telescopes within the bushing 25, a guide support 71 being clamped to the lower end of the bushing 25 as at 72. With the arrangement as shown in Fig. 5, the movement of the movable contact 29 is more slow than that previously described but is entirely adequate for relatively low voltage service.

From the foregoing description, it will be apparent that we have provided an improved mounting arrangement for a circuit interrupter of the high voltage type in which the expense is considerably reduced by employing a single high voltage bushing. The high voltage bushing 25 is supported intermediate its ends by the grounded supporting framework 24. The shaft 45 may be employed to simultaneously effect the operation of one or more other interrupters, not shown, each of which may be supported by a grounded framework 1. Thus, by rotation of the shaft 45 simultaneous operation of all the interrupters, for example controlling the three phases of a transmission line, may be effected.

By employing a telescoping construction for the movable contact structure, considerable longitudinal space is saved. Also, the operating mechanism, particularly as shown in Fig. 5, is simple and requires very little lateral space.

Thus, the lateral dimensions of the interrupter need be only slightly larger than the space necessary to house the arc extinguishing unit 26.

From the foregoing, it will be apparent that the interrupter of our invention consists essentially of one condenser bushing, with its current transformers and potential device, a tank consisting of an insulating tube for support and a porcelain weather casing. The insulating tube is a tension member and takes all the shock due to breaker operation, while the porcelain is always resiliently supported and clamped in compression.

The general breaker arrangement not only results in a much cheaper breaker but also one which can be serviced more easily and permits of greater switch yard flexibility. Such an interrupter may be mounted in the towers or on top of the tower or in the roof of a building to save ground space or extending through the roof thus replacing a wall bushing.

Although we have shown and described specific constructions, it is to be clearly understood that the same were merely for the purpose of illustration and that changes and modifications may readily be made therein by those skilled in the art without departing from the spirit and scope of the appended claims.

We claim as our invention:

1. In a circuit interrupter, supporting means at ground potential, a casing a substantial portion of the side walls thereof being of insulating material and providing for a difference of potential between the ends of the casing, only a single terminal bushing for the interrupter, the terminal bushing including an elongated conductor having insulation disposed thereabout, the terminal bushing being supported intermediate the ends thereof by the grounded supporting means, the terminal bushing projecting into one end of the casing and having the interior end thereof terminating adjacent the mid-portion of the casing, a stationary line terminal disposed at the external end of the terminal bushing, a substantially stationary contact and line terminal means for the interrupter both disposed adjacent and at the potential of the other end of the casing, a movable contact disposed within the casing and movable during the opening operation toward the interior end of the terminal bushing, and actuating means for the movable contact carried by and at the potential of the grounded supporting means.

2. In a circuit interrupter, supporting means at ground potential, a casing a substantial portion of the side walls thereof being of insulating material and providing for a difference of potential between the ends of the casing, only a single terminal bushing for the interrupter, the terminal bushing including an elongated conductor having insulation disposed thereabout, the terminal bushing being supported intermediate the ends thereof by the grounded supporting means, the terminal bushing projecting into one end of the casing and having the interior end thereof terminating adjacent the mid-portion of the casing, a stationary line terminal disposed at the

external end of the terminal bushing, a substantially stationary contact and line terminal means for the interrupter both disposed adjacent and at the potential of the other end of the casing, a movable contact telescopically related to the terminal bushing and telescoping into the terminal bushing during the opening operation, means electrically interconnecting the movable contact with the elongated conductor, and actuating means for the movable contact carried by and at the potential of the grounded supporting means.

3. In a circuit interrupter, supporting means at ground potential, a casing a substantial portion of the side walls thereof being of insulating material and providing for a difference of potential between the ends of the casing, only a single terminal bushing for the interrupter, the terminal bushing including an elongated conductor having insulation disposed thereabout, the terminal bushing being supported intermediate the ends thereof by the grounded supporting means, the terminal bushing being supported intermediate the ends thereof by the grounded supporting means, the terminal bushing projecting into one end of the casing and having the interior end thereof terminating adjacent the mid-portion of the casing, a stationary line terminal disposed at the external end of the terminal bushing, a substantially stationary contact and line terminal means for the interrupter both disposed adjacent and at the potential of the other end of the casing, a movable contact disposed within the casing and movable during the opening operation toward the interior end of the terminal bushing, means electrically interconnecting the movable contact with the elongated conductor, actuating means for the movable contact carried by and at the potential of the grounded supporting means, and an insulating operating rod disposed within the casing extending substantially longitudinally of and external to the terminal bushing and mechanically interconnecting the actuating means at ground potential and the movable contact.
